UNITED STATES PATENT OFFICE.

ORLANDO R. ERWIN, OF FOREST HILLS, NEW YORK, ASSIGNOR TO FOAMITE-CHILDS CORPORATION, OF NEW YORK, N. Y., A CORPORATION OF DELAWARE.

FIRE-EXTINGUISHING APPARATUS.

Application filed November 12, 1920. Serial No. 423,511.

The invention relates to foam fire extinguishing apparatus, and particularly to a novel and efficient fire engine of the twenty or forty gallon type for storing and mixing 5 the soda and acid solutions.

It is a primary characteristic of this invention that the direction of tipping of the extinguisher is predetermined and that the pressure equalizer tube or tubes or openings 10 from the mixing chamber to one or both of the solution containers are located so as to be on the top side when the extinguisher is tipped to bring it into action, a regulated non-gurgling even flow of the solutions into 15 the mixing chamber being thus effected automatically, that is, without special thought or variation of procedure in the operation of the extinguisher. Eccentric mounting of the main container with respect to the axis on 20 which it turns in tipping may be the factor predetermining the direction of tipping. The projecting handle also may indicate and insure such predetermination. The wheeled engine structure in addition to providing 25 for trundling insures ready tipping in the predetermined direction and, given also the relative equalizer arrangement stated, effects the desired uniform non-gurgling operation. This eliminates undue pressure 30 strains in the container, which may therefore be made of relatively light material on which account the apparatus, though of the 40 gallon type, may be easily transported and operated. Furthermore, though the outlets for 35 both solution containers into the mixing chamber be normally open, the engine may by grasping the projecting handle be dragged or pushed in a position oblique but not sufficiently oblique to produce solution dis- 40 charge, or at all events discharge of both solutions, and the arrangement is substantially splash proof in the transportation of the engine.

Referring to the drawings:

Figure 1 is a side elevation of the upright engine.

Figure 2 is a cross section of the engine when tilted into active position.

Figure 3 is a cross section on the line 3-3, 50 Figure 2, and

Figure 4 is a cross section on the line 4-4, Figure 2.

The body of the engine comprises an outer shell 5, having a concave bottom portion 6, 55 preferably integral with said portion 5.

Mounted on top of the shell and fixed thereto as by riveting is a dome portion 7 forming the top of the engine and provided with charging opening 8 and discharging opening 9. The charging opening is normally 60 closed in any desired way as by a thimble 10 fitted therein having an outwardly turned flange portion 11 secured to the dome, and a threaded neck 12 which receives the threaded collar portion 13 of a rotatable hand wheel 65 cap 14, which with a gasket 15 between the neck and the hand wheel cap completes the closure. In the discharge opening 9 is fitted an internally threaded bushing 16 adapted to receive pipe 17, to which is connected a 70 fire hose 18. The shell 5 is supported for purposes of transportation upon the beam 19, on the outer ends of which are mounted for rotation wheels 20, the shell being retained on the said beam by any desired 75 means, that shown in the drawings being a strap 21 encircling the said shell and connected at its opposite ends to beam 19, these parts being so arranged that when the engine is in erect position as shown in Figure 1, 80 the strap is in the horizontal plane of the axis of wheels 20, by which arrangement the engine is properly supported when in erect position. The mounting of the extinguisher to one side of the wheel axis predetermines 85 the direction of tipping. The handle 22 fixed to the upper portion of the shell and projecting in the direction of tipping also serves this purpose being in itself a sufficient predetermining means. The handle is 90 grasped in pushing or pulling the apparatus and also provides supporting means for the shell when in final tilted position, as shown in Figure 2.

For proper storing of the solutions and 95 for efficient generation and emission of the foam, the engine is subdivided into three compartments, two of which are solution containers and the other a mixing chamber. The preferred arrangement shown in the 100 drawings comprises a partition in the form of a disk 23 connected to the interior surface of the body portion of the shell as by riveting and subdividing the engine into an upper mixing chamber 24 and a lower body portion 25, the said body portion being further subdivided into two solution chambers, as by tank 26 supported from the disk 23, 105 the said tank separating the body portion into a basic solution compartment 25 and 110

an acid solution compartment 27. Solution outlets 28 and 29 formed in the disk 23 respectively place the B and A compartments in communication with the mixing 5 chamber. Extension of the solution outlet 29 above the bottom of the mixing compartment by the short tube 30 secured in disk 23 tends to prevent splashing of A solution. Easy flow by gravity of the solutions from 10 the solution compartments into the mixing chamber is insured by providing means for equalizing the pressure of the generated foam on the solutions at the solution outlets, such means comprising equalizing pressure inlets 30' and 31 formed in the disk 23, these inlets comprising in the preferred form tubular members 32 and 33 extending into the solution chambers and terminating near the bottom portions thereof. Splashing 15 of A solution is further guarded against by extending equalizing tube 32, when present, into the mixing chamber as shown in Figure 2, and these provisions along with the handle 22, eliminate the need of a screw 20 valve to be operated as heretofore customary for opening the acid or basic container. The other end of tube 32 is fixed to an angle iron 34 connected to any convenient portion of the tank 26, the said tank being 25 in turn supported by means of plate 35 secured to the shell or the tubular member 33.

The engine tipped to the proper angle in the predetermined direction and trundled if 30 necessary to reach the fire, is brought into operation by tilting to active position, as in Fig. 2, whereupon the solutions flowing out of the solution chambers through the solution outlets into the mixing chamber 40 and being there thoroughly mixed generate the fire extinguishing foam, which discharges through the fire hose 18. The feeding of the solutions is automatically regulated by the solution outlets, this providing 45 a regulated mixture, thus preventing undue pressure strains in the container. Some of the generated foam passes from the mixing chamber to the solution chambers by way of the equalizing pressure means, thus 50 equalizing the pressure on the solutions and providing for the steady and non-gurgling flow of the solutions into the mixing chamber.

While I have shown my device in the preferred form, it will be obvious that many changes and modifications may be made in the structure disclosed without departing from the spirit of the invention, defined in the following claims:

60 1. A fire extinguisher having means predetermined the axis on which it is adapted to be tipped and the direction of tipping, comprising two solution containers, and a mixing chamber, outlets from both 65 containers to said mixing chamber, and a pres-

sure equalizer opening from the mixing chamber to one of said solution containers arranged on the side of the extinguisher which is highest when tipped.

2. A fire extinguisher having wheels by 70 which it is transported and adapted to be tipped by turning on the axis of said wheels in a predetermined direction, comprising a soda solution container, an acid solution container and a mixing chamber, outlets from 75 both said containers to the mixing chamber, and a pressure equalizer opening from the mixing chamber to each of said solution containers arranged on the side of the extinguisher which is highest when tipped. 80

3. A fire extinguisher having wheels by 85 which it is transported and adapted to be tipped by turning on the axis of said wheels in a predetermined direction, comprising two solution containers and a mixing chamber, a foam outlet from said mixing chamber on the side of the extinguisher which is highest when tipped, solution inlets to said mixing chamber from both said containers on the side of the extinguisher which is lowest 90 when tipped, and a pressure equalizer opening from the mixing chamber to one of said containers arranged on the side of the extinguisher which is highest when tipped.

4. A wheeled fire extinguishing engine 95 adapted by tilting of the engine for the commixing of chemical solutions to produce a fire extinguishing foam, comprising an outer shell, a wheeled support for said shell, these parts being so constructed as to support the shell normally in erect position and to permit the shell to be moved substantially 100 90 degrees from the said erect position to a tilted position and so supported, means subdividing the interior of the shell into solution compartments provided with solution outlets and a mixing chamber communicating by means of the said outlets with the solution compartments and a discharge opening formed in the mixing chamber; the 105 said solution outlets being located to one side and the discharge opening to the opposite side of the longitudinal axis of the shell with the discharge opening located at the top when the engine is moved to tilted position 110 115 whereby upon tilting the engine the solutions will flow to the bottom of the mixing chamber and there commix to produce a fire extinguishing foam which freely rises in the mixing chamber for discharge through the 120 said discharge opening.

5. A wheeled fire extinguishing engine 125 adapted by tilting of the engine for the commixing of chemical solutions to produce a fire extinguishing foam, comprising an outer shell, a wheeled support for said shell, these parts being so constructed as to support the shell normally in erect position and to permit the shell to be moved substantially 90 degrees from the said erect position 130

to a tilted position and so supported, means subdividing the interior of the shell into solution compartments provided with solution outlets and a mixing chamber communicating by means of the said outlets with the solution compartments, a discharge opening formed in the mixing chamber; the said solution outlets being located to one side and the discharge opening to the opposite side 5 of the longitudinal axis of the shell with the discharge opening located at the top when the engine is moved to tilted position where- 10

by upon tilting the engine the solutions will flow to the bottom of the mixing chamber and there commix to produce a fire extinguishing foam which freely rises in the mixing chamber for discharge through the said discharge opening and equalizing pressure means connecting the mixing chamber with the said solution compartments. 15

Signed at New York, in the county of New York and State of New York, this 10th day of November, A. D. 1920.

ORLANDO R. ERWIN.
